UNITED STATES PATENT OFFICE

JOHN A. McGREW, OF ALBANY, NEW YORK, ASSIGNOR TO BETHLEHEM STEEL COMPANY, A CORPORATION OF PENNSYLVANIA

LOCOMOTIVE BOOSTER FRAME

Original application filed July 14, 1927, Serial No. 205,680. Patent No. 1,742,610, dated January 7, 1930.
Divided and this application filed February 21, 1929. Serial No. 341,711.

My invention relates to motorized railway trucks of the auxiliary locomotive booster type and relates more particularly to the casing or frame of the same. The present application is a division of my copending application Serial No. 205,680, filed July 14, 1927, now Patent No. 1,742,610, issued January 7, 1930.

The present invention relates to motorized railway trucks and particularly to locomotive auxiliary propulsion units designed and constructed to assist a locomotive in propelling a train in starting under heavy load or to assist the same in moving upgrade at relatively low speed.

In accordance with the invention, an auxiliary propulsion unit is provided which is particularly suitable for utilization in connection with a locomotive tender truck and which has a number of novel and important features of construction. Certain features of the invention are, however, of general application in the art, as will be apparent upon inspection of that form of the invention which is herein described by way of example.

One important feature of the invention consists in the provision of means for readily draining liquid condensate from the steam cylinders of the auxiliary propulsion unit. It will be understood that the auxiliary propulsion unit itself is positioned at some distance from the main power plant or boiler of the locomotive and that, in cold weather and especially before the cylinders of the unit have become sufficiently warm after the energizing steam is caused to flow to the same, there is a strong tendency for condensation to occur. Heretofore it has been generally deemed necessary to provide special drain valves in connection with the cylinders of these auxiliary propulsion units. In accordance with this invention, however, the necessity for the use of these drain valves is dispensed with, novel and improved means being provided for readily and continually draining the cylinders of any liquid condensate which may be formed therein.

Other novel features will be more fully understood from the following description and claims taken in connection with the ac-

companying three sheets of drawings, in which:

Figure 1 is a plan view of an auxiliary propulsion unit mounted on a railway vehicle truck embodying my invention;

Figure 2 is a longitudinal section taken on line 2—2 of Fig. 1;

Figure 3 is a longitudinal section taken on line 3—3 of Fig. 1;

Figure 4 is a longitudinal section taken on line 4—4 of Fig. 1;

Figure 5 is a transverse section taken on the line 5—5 of Fig. 4;

Figure 6 is a transverse section taken on line 6—6 of Fig. 4; and

Figure 7 is a detail section taken on the line 7—7 of Fig. 2.

Referring to the drawings, the frame of the locomotive booster engine is indicated generally by the numeral 10 having spaced overhanging journal bearings 11 and 12 formed at its forward end and adapted to be bolted to a bearing cap and to engage the load bearing axle 13 on which is mounted centrally between the bearings 11 and 12 the driven gear 14 which meshes with a pinion 15 keyed to the main driving shaft 16 which is journaled in spaced bearings 17 extending upwardly from the base plate of the frame at an intermediate point thereof.

The main base frame 18 comprises an integral structure having a bottom wall 19, upwardly extending side walls 20 and 21, front walls 22 to which the overhanging journal bearings 11 and 12 are formed and rear wall 23. The main base frame 18 is also reinforced at intermediate points by means of longitudinal ribs 24 and 25 and transverse ribs 26 and 27.

The bottom wall 19 of the main frame extends rearwardly beyond the back wall 23 as at 28 and is integrally connected to the cylinder casings 29 and 30 and steam chests 31 and 32. The steam chests and cylinders are further connected to the bottom wall extension 28 and back wall 23 by means of vertical ribs 33 and 34, ribs 34 being connected together by means of a bracket 35 by means of which the rear end of the booster frame is suspended from the truck bolster 36, as indicated in dotted lines in Fig. 4.

100

The cylinder casings 29 and 30 and steam chests 31 and 32 are each provided with pistons 37 and 38 respectively. Pistons 37 are each reciprocated by fluid pressure and 5 adapted for rotating the main drive shaft 16 through the piston rods 39, crossheads 40, pitmen 41 connected thereto and to the crank arm 42 mounted on the drive shaft 16.

The supply of fluid pressure to the cylinders are each controlled by the rotation of the 10 driving shaft 16 through the piston rods 43, crank arms 44 and 45 secured to rock shaft 46, crank arm 45 being connected by means of the pitman 48 to the eccentric crank 49, said eccentric arm 49 being pivoted as at 50 to the crank arm 42 which is keyed to the end of the main driving shaft 16 and connected to the pitman 48 as at 51, as more clearly described and claimed in my copending parent application 15 above mentioned, but as this mechanism forms no part of this application a more detailed description of same is not deemed necessary.

Intermediate the cylinders 29 and 30 are 20 the steam chests 31 and 32 which are connected with the steam inlet conduit 52 by the steam supply passages 53 and 54 in the steam chests and communicate centrally through ports 55 and 56 in the slide valve 25 liners 57, to the pistons of the slide valves 38, thence it is adapted to pass when the slide valves 38 are reciprocated to the steam ports 58 and 59 in the liners to enlarged ducts 60 and 61 through ports 62 and 63 in 30 the cylinders 29 and 30 where it is finally exhausted into passages 64 and 65 having downwardly inclined or sloping bottom walls 35 66 which enables any condensation from the cylinders and steam chests to be discharged 40 through exhaust outlet pipe 67.

Although I have shown and described my invention in considerable detail, I do not wish to be limited to the exact and specific details shown and described, but may use 45 such substitutions, modifications or equivalents thereof as are embraced within the scope of my invention, as pointed out in the claims.

Having thus described my invention what 50 I claim and desire to secure by Letters Patent is:

1. In an engine frame, the combination 55 of a cylinder having ports, a steam chest, a piston within said cylinder, a crank shaft, a rod connecting the latter to said piston, said steam chest being provided with a steam inlet passageway and a steam outlet passageway, said outlet passageway being open to 60 said cylinder and sloped downwardly so that condensate formed in the cylinder will flow therefrom by gravity, a valve within said steam chest for controlling said passageways, and means to connect said valve to said crank shaft.

2. In a locomotive booster frame, compris-

ing an integral structure, a main frame having a bottom wall with upwardly extending flanged edges and side walls, longitudinal and transverse ribs connecting the flanged edges and side walls, said bottom wall having a rearward extension, cylinders and steam chests spaced apart from the main frame and connected therewith by means of the rearwardly extending bottom wall, and vertical ribs connecting the main frame cylinder and 70 steam chest casings together. 75

3. In a locomotive booster frame, comprising an integral structure, a main frame formed with journal bearings at its forward end and having bottom, side and end walls, 80 the bottom wall formed with a rearward extension, a plurality of cylinders and steam chests in spaced relation with the main frame formed integral with the bottom wall extension, vertical ribs connecting the main frame cylinders and steam chests together, outlet passageways for the cylinders, said outlet passageways being open to the cylinders having downwardly inclined bottom walls so that the condensate formed in the cylinders 90 will flow therefrom by gravity.

4. In a locomotive booster frame, comprising an integral structure, a main frame formed with journal bearings, bottom, side and end walls, cylinders and steam chests spaced apart 95 and rigidly supported upon the main frame, outlet passageways for the cylinders and steam chests, said outlet passageways being open to the cylinders and steam chests and having downwardly inclined bottom walls so that 100 the condensate from the cylinders will flow therefrom by gravity.

5. In a locomotive booster frame, an integral structure, comprising a main frame, cylinders and steam chests rigidly supported 105 upon and having steam outlet passageways, said passageways having downwardly inclined bottom walls adapted to convey the condensate from the cylinders and steam chests by gravity to a common point of discharge. 110

6. An auxiliary propulsion unit comprising a frame, spaced horizontal parallel steam cylinders thereon, said cylinders having steam inlet and exhaust ports therein, means 115 for leading steam from a point intermediate the cylinders to the respective inlet ports thereof, and passageways for leading exhaust steam from the cylinder exhaust ports to a point of discharge intermediate said cylinders, said passages having floors downwardly and inwardly inclined to permit the free flow of liquid condensate from said cylinders. 120

7. An auxiliary propulsion unit comprising, in combination, a frame, spaced parallel steam cylinders thereon, said cylinders having steam inlet and outlet ports therein, the outlet ports having portions located at the 125 lowermost points of the cylinders, means for 130

leading steam to the cylinder inlet ports, and passageways for leading steam from the cylinder outlet ports, the floors of said passageways sloping downwardly from the cylinder exhaust ports so that liquid condensate can flow freely from the cylinders under the influence of gravity.

8. An auxiliary propulsion unit comprising a steam cylinder having inlet and outlet ports formed therein, a passageway for conducting steam to the inlet port of the cylinder, and a second passageway for conducting steam from the outlet port, the floor of the second passageway being inclined downwardly from the cylinder outlet port so that liquid condensate will flow from the cylinder by gravity.

9. An auxiliary propulsion unit comprising a steam cylinder having inlet and outlet ports therein, the outlet port being positioned to permit the egress of condensate tending to collect at the lowermost point of the cylinder, a passageway for leading steam to the inlet port, and a passageway for leading steam and condensate from the exhaust port.

In testimony whereof I hereunto affix my signature.

JOHN A. McGREW.
